(57) **CLAIM**

The ornamental design for a hinge for modular disc storage case, as shown and described.

DESCRIPTION

FIG. 1 is a front perspective view of a hinge for modular disc storage case, showing my new design;

FIG. 2 is a perspective view in opened condition thereof;

FIG. 3 is a front view thereof;

FIG. 4 is a rear view thereof;

FIG. 5 is a left end view thereof;

FIG. 6 is a right end view thereof;

FIG. 7 is a top plan view thereof; and,

FIG. 8 is a bottom plan view thereof.
